(57) **CLAIM**

The ornamental design for a sleeve for cast, as shown and described.

DESCRIPTION

FIG. 1 is a perspective view of our design;

FIG. 2 is a front elevational view of our design;

FIG. 3 is a side elevational view of our design; and,

FIG. 4 is a top view of our design.

The features shown in broken lines, if any, are shown for illustrative purpose only and form no part of the claimed design.

1 Claim, 2 Drawing Sheets

FIG.1

FIG.2
